UNITED STATES PATENT OFFICE.

CHARLES L. WRIGHT, OF NEW HAVEN, CONNECTICUT, ASSIGNOR TO
SARGENT & CO., OF SAME PLACE.

DESIGN FOR A COFFIN-PLATE.

SPECIFICATION forming part of Design No. 14,013, dated June 26, 1883.

Application filed May 7, 1883. Term of patent 7 years.

To all whom it may concern:

Be it known that I, CHARLES L. WRIGHT, of New Haven, in the county of New Haven and State of Connecticut, have invented a new

5 Design for Coffin-Plates; and I do hereby declare the following, when taken in connection with accompanying drawing and the letters of reference marked thereon, to be a full, clear, and exact description of the same, and which 10 said drawing constitutes part of this specification, and represents a face view.

This invention relates to a design for coffin-plates; and it consists in the configuration and ornamentation, as shown in the accompanying 15 illustration. The lower side and two ends form the three sides of a parallelogram, the upper or fourth side raised by irregular lines from the ends toward the center. At the center top is the representation of a pair of 20 gates as hinged each to a post, the posts standing upon a base, and the gates represented as partially open. Above the gates is a panel adapted to receive the words "The Gates

"Ajar," or other appropriate words. From each side of the representation of the gates 25 springs a tracery of scroll-work on a basket-ground.

The essential feature of this design is the representation of the partially-opened gates hinged to their respective posts. Other or- 30 namentation may be substituted at each side, or that ornamentation may be omitted altogether.

I claim—

The herein-described design for coffin-plates, 35 consisting of the plate having the upper edge projecting, and on the face, at the center upper part, the representation of a pair of gates hung to the posts and represented as partially open, as shown in the accompanying illustration.

CHARLES L. WRIGHT.
